FINISH MATERIAL RETAINER

Maxwell C. Weaver and Ralph W. Hall, Cincinnati, Ohio, assignors to The Randall Company, Cincinnati, Ohio, a corporation of Ohio

Application September 27, 1945, Serial No. 618,828

3 Claims. (Cl. 296—135)

1

This invention relates to a finish material retainer or the like, such as may be classed with devices of the character disclosed in Weaver et al. Patent No. 2,276,530, dated March 17, 1942. One of the many uses for such devices is illustrated in the aforesaid patent, wherein is taught the application thereof to a vehicle roof structure for the purpose of holding taut a head lining fabric or other flexible material. For purposes of illustration and explanation, the device of the present invention will be disclosed with relation to a vehicle roof structure, although it is to be clearly understood that the device is capable of use under various other circumstances and conditions.

An object of the invention is to provide an improved finish material retainer which is structurally very simple, yet highly effective for maintaining a finish material of cloth or other flexible fabric in taut condition over a frame or other body to be covered.

Another object of the invention is to provide an improved finish material retainer which is so formed as to be easily bent in any direction so as to conform with complex curvatures of a frame or understructure to be covered with finishing cloth or fabric, the device possessing the advantage that none of its parts will become loose or detached or undesirably distorted in any other direction than is intended in rendering it conformable with the curvatures of the frame or understructure.

Another object is to provide a device of the character stated, which will firmly hold a finish sheet in place, smoothly and without puckering or tearing the sheet at the points of attachment.

A further object is to provide an improved finish material retainer which may be manufactured expeditiously and inexpensively from strip and rod materials, preferably metal, which in the first instance may be purchased at low cost.

The foregoing and other objects are attained by the means described herein and illustrated in the accompanying drawing, in which:

Fig. 1 is a perspective view of the finish material retainer, showing an attachment plate applied thereto.

Fig. 2 is a cross-sectional view showing the retainer applied to the roof structure of a vehicle.

2

Fig. 3 is a view similar to Fig. 1, showing the retainer bent in the plane of its mounting tabs, for application to a curved surface.

Fig. 4 is a top view of the retainer, in which it is shown bent laterally to conform with another curvature of the understructure or vehicle roof.

Fig. 5 is a side elevational view of a modified form of the finish material retainer.

Fig. 6 is an enlarged cross-sectional view taken on line 6—6 of Fig. 5.

The understructure or frame selected for the purpose of this description, is illustrated by Fig. 2 as a portion of a vehicle roof, wherein 8 indicates the roof rail, 9 the roof bow, and 10 the roofing sheet which is usually of metal or other substantially rigid material. The character 12 indicates a sheet of flexible finish material such as woven cloth, fabric, leatherette or the like, serving as a covering material for the roof bow and rail interiorly of the vehicle. The finish material may be fixed to the roof bow in any suitable manner, and is to be drawn taut along the inside face 13 of the structural member 8 of the roof. To so anchor the free end 14 of the finish material sheet, is the function of the retainer herein disclosed.

Referring to Fig. 1, the retainer is indicated generally by the character 15, and will be seen to comprise a narrow sheet of metal or other suitable material formed about a reinforcing wire or spine 16 to provide a smooth cylindrical bead 17. The spine is an elongated member which is of such cross-sectional shape as to be bendable in any direction with equal facility. In the example shown, the spine is circular in cross-section, or substantially so, in order to meet the foregoing requirement. As is obvious, it might also be elliptical or polygonal in cross-section to produce the result desired.

Along a line 18 which is parallel to the axis of the spine, the strip may be bent upwardly to furnish a narrow fin 19 along which is formed the series of barbs or prongs 20, and the alternately disposed mounting tabs 21 which lie preferably in the plane of the prong bases 22. At locations intermediate the base and the point of each prong, the material is angularly bent toward one side in order to dispose the pointed portion of the prong angularly to the base there-

of. The points of the prongs, as illustrated by Fig. 4, extend laterally beyond the bead 17, whereas the prong bases 22 and the mounting tabs 21 rest substantially in a plane which includes also the axis of the spine.

By means of spot welds, rivets, or other fastening means 23, selected mounting tabs of the finish material retainer may be firmly secured to the base 24 of an attachment plate, said plate having a head 25 offset from the plane of the mounting tab, by means of a reversely curved neck portion 26 formed on the plate. The head of the plate may be apertured as at 27 to receive screws or other fastening devices 28 which fasten the attachment plate to the frame or structural member 8, as illustrated by Fig. 2. It may be noted that the head 25 of the attachment plate extends to one side of the bead 17, for a distance which does not exceed the reach of the prong points beyond the bead. By reason of this relationship, the prong point as shown in Fig. 2, will substantially contact the inside face 13 of the structural member 8 when the head of the attachment plate is fixed thereto, as by means of the fastener 28. With this understanding, it will be readily appreciated that by using a tool to force the free end 14 of the finish material sheet upwardly along the face 13 of the roof rail, said free end may be extended past the series of prongs 20 so that the prongs may grip the material and hold it tightly in snug covering relationship about the bead 17. Due to the upward and inward direction of projection of the prongs, it is impossible for the finish material to retract and become loose about the bead 17, once it has been placed in gripping relationship with the prongs.

It may here be noted that the diameter of bead 17 is sufficiently in excess of the thickness of the prong base, as to provide an obstruction or a limiting effect upon any tendency of the finish material to slide down onto the bases of the prongs, while penetrated by the prong points. By this means, there is avoided the likelihood of the triangular prongs slitting the finish material where penetrated, and permitting it to sag and become loose about the circumference of the retainer bead.

The material of the attachment plate and the mounting lug, is sufficiently flexible to yield as the free end 14 of the finish material is projected upwardly beyond the points of the prongs by means of a thin plate-like tool. When the tool is removed, therefore, the bead 17 presses the finish material in the immediate vicinity thereof, toward and against the inside face 13 of the rail or structural member 8.

By referring to Figs. 3 and 4, it is evident that the retainer of the invention readily may be bent in the plane of its fin 19, or transversely of the fin. This enables the retainer to follow curvatures of the framework or understructure, which may in some instances be quite complex. The retainer may be bent not only transverse to and in the plane of the fin, but also in various intermediate directions angularly to the fin. Moreover, it may be twisted to a reasonable extent if necessary, to conform with such curvatures in the framework as may require such treatment.

Figs. 5 and 6 illustrate a modified form of the finish material retainer, wherein the prongs 30 and mounting tabs 31 are more closely spaced than in Fig. 1, each intermediate portion 32 between them being quite limited in extent and raised sufficiently above the bead to constitute a

short fin. In the modified form of the device, the triangular prongs are bent to one side of the plane of the mounting tabs, at approximately the level of the series of fins 32. Like the retainer of Fig. 1, the modified device includes the spine 33 and a surrounding bead 34, said spine and bead performing the same functions and bearing the same relationship to the prongs as previously mentioned herein. The mounting plate 35, which may be substantially like that illustrated by Figs. 1 and 4, may span one or more prongs in its attached relationship to two or more mounting tabs. Fixation of the mounting plate to the tabs may be effected at the locations 36, by means of spot welds or otherwise. In connection with Figs. 5 and 6, it is preferred that the mounting plate base 37 be applied to that face of a mounting tab which is opposed to the direction of extension of the prongs, this being clearly exemplified in Fig. 6. Referring to Fig. 5, it will be noted that the base portions of no two triangular prongs meet one another at a sharp angle, wherefore it is impossible for successive prongs to cut completely through the finish material along a continuous line, such as would result in severance of the material at the prongs. Moreover, the presence of bead 34 beneath the prongs precludes creeping of the finish material along the prongs toward the bases thereof, thereby further discouraging severance of the marginal edge of the lining material from the main body portion thereof by any cutting action of the prong edges. It should be noted that the head end of the attachment plate 35 extends no farther from the plane of the mounting tabs, than does the point of the prong, the reason for this being that the point of the prong is to be disposed as closely as possible to the surface upon which the attachment plate is secured, so as to be effective for gripping the finished material the instant that it is projected upwardly past the point of the prong. The prongs are sufficiently flexible to permit such insertion of the finish material past them.

From the foregoing, it should readily be appreciated that the present device is highly effective for its intended purpose, and that it may be manufactured expeditiously and at low cost with the use of simple and rapidly operating machinery. The several elements constituting the finish retainer are of such character as will enable rapid production with a minimum of expense.

We claim:

1. A finish material retainer of the class described, comprising a longitudinal strip including a bead, a reinforcing spine within the bead, a fin upstanding upon the bead radially of the spine, coplanar mounting tabs formed integrally with the fin at intervals along the length of the strip, and a series of prongs extending from a free edge of the fin in a common direction angularly to the plane of the mounting tabs, and attachment plates secured to certain of the mounting tabs, said plates each having a head in offset relationship thereto.

2. A finish material retainer of the class described, comprising a longitudinal strip including a bead, a reinforcing spine within the bead, a fin upstanding upon the bead radially of the spine, coplanar mounting tabs formed integrally with the fin at intervals along the length of the strip, and a series of prongs extending from the fin in a common direction angularly to the plane of the mounting tabs, and attachment plates secured to certain of the mounting tabs in offset

relationship thereto, and the offset of the attachment plates relative to the tabs being no greater in extent than the reach of the points of the prongs.

3. A finish material retainer of the class described, comprising a longitudinal strip including a bead, a reinforcing spine within the bead, a fin upstanding upon the bead radially of the spine, coplanar mounting tabs formed integrally with the fin at intervals along the length of the strip, and a series of prongs extending from a free edge of the fin in a common direction angularly to the plane of the mounting tabs.

MAXWELL C. WEAVER.
